United States Patent Office.

SAMUEL BOORN, OF LOWELL, MASSACHUSETTS.

Letters Patent No. 101,817, dated April 12, 1870.

IMPROVEMENT IN MECHANISM FOR STOPPING THE SHUTTLE IN LOOMS.

The Schedule referred to in these Letters Patent and making part of the same.

To all persons to whom these presents may come:

Be it known that I, SAMUEL BOORN, of Lowell, of the county of Middlesex and State of Massachusetts, have made a new and useful Invention having reference to Looms for Weaving Cloth; and I do hereby declare the same to be fully described in the following specification and represented in the accompanying drawings, of which—

Figure 1 is a top view, and

Figure 2, a side elevation of the shuttle-box of the lay of a loom, with my invention applied to such box and lay.

This invention has for its object the arresting or partially stopping the shuttle before it may strike the picker, the same being to prevent injurious indenting of the picker by the shuttle. This mechanism is not intended to dispense with the usual shuttle-binder to act against the side of the shuttle, as my said additional mechanism is to operate against the nose or pointed part of the shuttle.

In the drawings—

A denotes that part of the lay over which the shuttle-box B is situated.

C exhibits the picker;

D, the shuttle; and

F, the rod on which the picker is supported and runs or slides.

In advance of the picker, when in its rearmost position, there is applied to the inner surface of one side, *a*, of the shuttle-box, a stationary tapering projection, abutment, or buffer, G, having its inner surface cushioned.

Opposite to this buffer is another buffer, H, which is fastened to a movable arm, I, which, at or near one end is attached to the outer end or part *c* of the shuttle-box, so as to be capable of being moved horizontally toward or away from the abutment G.

The arm I is forced toward the said abutment G by means of a strong spring, K, projected from the lay, the whole being arranged substantially as represented in the drawings.

On the shuttle being driven into the box, the advancing nose of such shuttle will be caught between and by the stationary and movable buffers, the said

movable buffer giving way as the shuttle may progress toward the picker. The pressure and friction of the buffers on the nose of the shuttle will operate to arrest the shuttle more or less in its flight, and prevent it from bringing up against the picker with the force with which it would were it not for such appliances.

The buffer H, the arm I, and the spring K constitute what I term an "elastic presser," to operate with the stationary buffer or abutment G.

I am aware of the subject of the patent 35,394, granted to Elisha Robbins, and, therefore, do not claim such; it consisting in applying an elastic jaw to the shuttle-binder, to operate it and co-operate with another spring jaw, disposed within the rear part of the shuttle-box; nor do I claim the employment of a stationary stop and a single long bow spring in the side of the shuttle-box, such being to arrest a shuttle during its flight into such box; nor do I claim the employment of springs for such purpose.

Robbins's invention is to stop the shuttle-driver or picker-staff, and act as a spring to the binder. It only acts through the binder to effect stoppage of the shuttle before the picker; whereas, the stationary buffer and the elastic presser, as arranged and used by me, with reference to the picker and the shuttle, operates to check the shuttle only, in its movement up to the picker.

Furthermore, my elastic presser is pivoted to the shuttle-box at its rear end, and the spring is disposed on and screwed to the outside of the box, and is separate from the arm I. This arrangement enables the screws of the spring to be tightened or loosened, or the spring to be wedged, as occasion may require, to modify or adjust its presser on the arm I, as may be requisite from time to time.

I therefore claim the arm I, the jaws G H, and the spring K, as arranged, together and with the shuttle-box, as described, the jaws being in advance of the picker when at its rearmost position in the box, and the whole being to operate as specified.

SAMUEL BOORN.
